UNITED STATES PATENT OFFICE.

GILDEROY O. BURLEW, OF NEWARK, NEW JERSEY.

DENTAL ABRASIVE OR GRINDING DISK.

1,314,125.

Specification of Letters Patent. Patented Aug. 26, 1919.

Application filed October 30, 1917. Serial No. 199,224.

To all whom it may concern:

Be it known that I, GILDEROY O. BURLEW, a citizen of the United States, residing in the city of Newark, in the county of Essex and State of New Jersey, have invented certain new and useful Improvements in Dental Abrasive or Grinding Disks, of which the following is a full, clear, and exact description, such as will enable others skilled in the art to which it pertains to make and use the same, reference being had to the accompanying drawings, and to numerals of reference marked thereon, forming a part of this specification.

It is customary in dental work to employ wheels or disks fixed upon a revolving mandrel for the purpose of grinding, cutting, and polishing teeth. These grinding wheels or disks are mounted upon a steel mandrel and when so mounted the grinding wheel or disk becomes a rigid and unyielding body which causes great discomfort and pain in preparing abutments for crowns and bridge work.

Furthermore, the periphery of the grinding wheels or disks so mounted have a tendency to become irregular thereby causing great shock and impairing the efficiency of the work.

A grinding disk or wheel so mounted will run at an exact right angle to the revolving mandrel upon which it is fixed.

The object of my invention consists in providing the central opening or aperture of a grinding disk with recesses, and securing into said recesses a soft yieldable center core, said center core being provided with a central hub having projections formed upon its central hub to engage with the said recesses for securing said center core to said disk.

A still further object of my invention is to provide grinding wheels or disks which shall be positive yet effective in operation, simple and inexpensive in construction, and durable in use.

These objects I perform in the preferred embodiment of my invention, which I have illustrated in the accompanying drawings, to which reference is had, and in which similar reference characters indicate corresponding parts in the several views.

In the drawings,

Figure 1 represents a plan view of my improved device.

Fig. 2 represents a sectional view taken on line $x-x$ of Fig. 3.

Fig. 3 represents a plan view of my improved device representing the center core in section.

Figs. 4 and 5 represent respectively a plan view and a side elevation of the center core removed from the disk.

Fig. 6 represents a plan view of a modified form of my improved device; and

Fig. 7 represents a mandrel and applied disk.

In the drawings, 1 represents a disk suitable for abrading, cutting, polishing, etc., according to the work to be done. The disk 1 is provided with a central opening 2 for the reception of the yieldable center core 3. This yieldable center core is provided with an opening 4 by means of which it is secured upon the mandrel. The center core 3 as illustrated in the drawings is provided with a central hub 5 on each side of which are integrally formed preferably thin rubber flanges 6—6 designed to engage with the opposite faces of the disk 1 adjacent to the opening 2 therein and by means of which the center core is buttoned or secured to the disk.

From an inspection of Figs. 2 and 3 of the drawings it will be noted that the diameter of the hub 5 is slightly less than the diameter of the opening 2 in the disk and that the same is provided with a plurality of projections 7 the distance across said projections being slightly greater than the diameter of the opening 2 in order that the projections may engage with the bore or opening 2 of the disk.

The center core 3 is secured or buttoned to the disk by forcing the same through the opening 2 thereof.

It will thus be seen that I have provided a disk or wheel of the character described which will hold its angular position upon the mandrel with perfect firmness and security and at the same time will readily permit the changing of its angular position upon the mandrel.

In the modified form illustrated in Fig. 6 I have shown the central hub 5 provided with a series of projections 7 designed to be received into a corresponding series of recesses 8 formed in the bore or opening 2 of the disk 1 to provide additional holding means for more firmly securing if desired.

the center core to the disk to prevent accidental turning of the disk.

In Fig. 7 of the drawings the dotted lines represent the positions that my improved device will assume if it be desired to have the disk operate at an angle different from a right angle to the mandrel.

Experience has demonstrated that the device above described is a highly efficient one, and while the device shown is the preferred embodiment of my invention, I do not care to restrict myself to the exact details of construction described, it being obvious that minor variations thereof not involving the exercise of invention, may be made by any skilled mechanic, and such departures from

what is herein described and claimed, not involving invention, I consider as within the scope and terms of my claim.

I claim:

A grinding disk provided with a central opening having recesses formed therein and a soft yieldable center core provided with a central hub having projections formed upon its central hub to engage with said recesses for securing said center core to said disk.

This specification signed and witnessed this 27th day of October, 1917.

GILDEROY O. BURLEW.
